UNITED STATES PATENT OFFICE.

ALAN R. FERGUSON, OF BUFFALO, NEW YORK.

TOY SEMAPHORE SIGNAL TOWER.

Application filed November 7, 1922. Serial No. 599,604.

To all whom it may concern:

Be it known that I, ALAN R. FERGUSON, a citizen of the United States, residing at Buffalo, in the county of Erie and State of New York, have invented certain new and useful Improvements in Toy Semaphore Signal Towers, of which the following is a specification.

This invention relates to toy railway accessories especially adapted to be used in connection with toy railways, and particularly to an improved toy railway warning or signaling device, an object of the invention being to provide an improved toy signal device of this class which will be relatively cheap and easy to manufacture, and strong and durable in use.

A further object of this invention is to provide a toy signal device such as a toy semaphore signal tower having wire formed supporting means, the improved construction enabling the device to be made at a minimum of expense and with a reduction of the number of steps in the manufacture, and at the same time providing a device of increased strength and durability.

A further object of this invention is to provide a toy semaphore signal tower wherein the semaphore arm or arms are adapted to be maintained in predetermined position in an improved manner.

Other objects of this invention will appear in the following description thereof, reference being had to the accompanying drawings forming a part of this specification, wherein like reference characters indicate corresponding parts in the several views, and wherein Fig. 1 is a front elevation illustrating an embodiment of my invention; Fig. 2 is a rear elevation thereof partly broken away; Fig. 3 is a cross section taken substantially on line 3—3 of Fig. 2; Fig. 4 is a sectional plan view taken substantially on line 4—4 of Fig. 1; Fig. 5 is a rear elevation illustrating a modified form and Fig. 6 is a detailed elevation partly broken away illustrating a form of construction.

In its preferred form I have illustrated this improved toy railway warning or signalling device in the form of a toy semaphore signal tower which comprises in general a supporting stand including an upright supporting member and movable semaphore arms connected to the upright member and adapted to be shifted into various positions with relation thereto. The support-

ing stand is preferably formed from a single length of metal, and in the present instances comprises a wire of suitable length which is bent to form a supporting base and an upright member extending therefrom, the semaphore arms being carried by the upright member.

In the drawings it will be seen that the supporting stand is formed from a wire which is bent or coiled to provide a supporting base 9, the wire being bent inwardly at 10 preferably in the plane of the coil forming the base and to a point substantially midway thereof, and then is bent upwardly to form an upright supporting member 11, of suitable height. The supporting stand may be provided with any suitable number of signal or semaphore arms, in the present instance two being shown by way of example. In the present instance the semaphore arms 12 are carried by the supporting upright 11 through the medium of clamps or brackets 13, each clamp or bracket 13 being bent to securely embrace the wire 11 and is held in fixed position with relation thereto. The signal arms 12 are pivoted at 20 to the laterally projecting portion of the clamps or brackets 13, and it will be noted that these pivotal connections are located in spaced relation from the wire upright 11. Each semaphore arm 12 is preferably stamped out of sheet material and is provided at the inner end with an elbow or offset portion 14, terminating in an enlarged end 15 constructed in the present instance for the purpose of providing self-locking means for the semaphore arm and also imitation signal lights. The enlarged end 15 is therefore provided with a pair of spaced circular depressions 95 or indentations 16. These depressions or indentations on the front side of the signal tower, see Fig. 1, may be lithographed in different colors to imitate signal lights. However, as illustrated in Fig. 3, instead of painting or lithographing the colored lights, colored disks 17 of paper or other suitable material may be pasted in the circular depressions 16.

The depressions 16 at the rear side of the signal tower, see Fig. 2, form bulges or projections 18 having a groove 19 lying therebetween. It will be seen therefore, that the projecting portions 18 form self-locking means for maintaining the arms 12 in horizontal position. Thus, when the semaphore arm is swung on its pivot 20, from its low-

ered position to a horizontal position, one of the projections 18 will frictionally engage the wire upright 11, and the resiliency thereof and of the arm will permit the projection 18 to pass over the wire upright 11 and permit the latter to become lodged in the groove 19. Therefore, in the extended position of the semaphore arm the locking projections 18 will grip the upright 11 therebetween and in swinging the arm upwardly or downwardly from a horizontal position the projections 18 will frictionally and resiliently resist such swinging movement. Furthermore, the semaphore arm may be maintained in various angular positions other than horizontal or vertical, due to the fact that either locking projections 18 will grip the wire upright 11 at various points on its surface and hold the arm in such adjusted position.

The wire upright 11 of Figs. 1 and 2 may be provided, as shown in Fig. 6, with integral projections at opposite sides thereof so as to resemble ladder steps. In such case, lugs 21 of suitable length may be formed from the metal of the wire member 11 and as illustrated the lugs may be arranged alternately at opposite sides so as to give the appearance of ladder steps. In the modified construction shown in Fig. 5 the supporting stand comprising the base 9 and upright member 11 may be constructed from wire as hereinbefore described. In this case however, the semaphore arm 22 is pivoted at 23 to the solid wire upright and the offset or elbow portion 24 of the arm is provided with spaced depressions 25 in which however the metal is bent away from the support 11. In this instance, the depressions are suitably colored to imitate signal lights without at the same time forming locking means. The shiftable locking means in this instance may comprise a wire 26 connected at 27 to the semaphore arm and having an open loop 28 at its opposite end which is adapted to embrace the wire base as shown in Fig. 5, for maintaining the arm in extended position. In order to lower the semaphore arm it is merely necessary in this case to release the loop 28 from the wire base. Thus, it will be seen that I have provided a toy signal device having a supporting stand of improved construction, and also having signal semaphore arms carried by the stand and provided with shiftable locking means for maintaining the arm or arms in various positions, in the preferred form each swinging semaphore arm being provided with self-locking means. It will be further noted that the self-locking means may comprise depressions adapted to form imitation signal lights at one side and gripping means at the opposite side, the depressions thereby performing a double

It will be understood that by describing in detail herein any particular form, structure, or arrangement it is not intended to limit the invention beyond the terms of the several claims or the requirements of the prior art.

I claim as my invention:

1. In a toy railway signal device the combination of a wire formed base coil having one end extending radially inwardly and upwardly to provide a single vertical wire upright, and a sheet metal signal member secured to said upright. 75

2. In a toy railway signal device the combination of a base comprising a single wire coil having one end extending inwardly to substantially the center of said coil and upwardly to provide a single vertical wire upright, and a swinging semaphore signal member secured to said upright. 80

3. In a toy railway signal device the combination of a base comprising a single wire coil having one end extending inwardly to substantially the center of said coil and upwardly to provide a single vertical wire upright, a swinging semaphore signal member secured to said upright and means for releasably locking said member in predetermined position. 90

4. A toy railway accessory comprising a wire formed supporting base having an integral vertical wire member, and a railway warning or signalling device permanently fixed to said wire member. 95

5. A toy semaphore signal tower comprising a base, an upright member supported thereby, a movable arm carried by said member, and releasable locking means carried by the arm and coacting with said member for maintaining the arm in predetermined position. 100

6. A toy semaphore signal tower comprising a base, an upright member supported thereby, a movable arm carried by said member, said arm having an indented portion 110 coacting with said member for releasably maintaining the arm in predetermined position.

7. In a toy railway accessory the combination of a base comprising a wire coil having one end extending radially inwardly of the coil and upwardly to form a single vertical wire post, and a signal member secured to said wire post. 115

8. In a toy railway accessory the combination of a base, an upright post extending therefrom, a swinging arm carried by said post above the base, said arm and post having cooperating gripping means, said gripping means adapted to releasably hold the 125 arm in predetermined position.

9. A toy signal device comprising a supporting stand and a swinging arm carried by said stand, said arm having spaced projections for engaging the stand and form- 130

- ing means for releasably locking the arm in predetermined position.
10. A toy signal device comprising a supporting stand and a swinging arm carried by said stand, said arm having curved depressions constructed to form locking projections at one side and signal means at the opposite side.
11. A signal device of the class described comprising a supporting stand including a wire formed upright member, clamping means connected to said member, and a swinging arm pivoted to said clamping means.
15. 12. In a signal device of the class described the combination of a supporting stand comprising a length of wire bent to form a coiled base and an upright post, a movable arm carried thereby, and shiftable locking means for maintaining the arm in predetermined position.
20. 13. In a signal device of the class described, the combination of a normally stationary upright post, and a movable signal arm carried thereby and having self-locking means operative upon movement of the arm into predetermined position.
25. 14. In a toy railway accessory the combination of a base comprising a wire coil having one end extending radially inwardly of the coil and upwardly to form a single vertical wire post, a movable signal member connected to said post and gripping means adapted upon shifting said member to releasably lock the member in position.
30. 15. In a toy railway accessory, the combination of a supporting base comprising a single convolution of wire free at one end and having its opposite end extended to form a radially disposed member terminating centrally of the coil in a single upright wire supporting member, and signal means attached thereto.
35. 16. In a toy railway accessory, the combination of a wire coiled base having one end extended to form a radially disposed portion terminating in a single wire upright post, and signal means attached thereto.
40. 17. A toy railway accessory including a wire supporting means comprising a wire formed base terminating at one end in a radially disposed wire member terminating in a single upright wire, and a warning or signal means attached to said upright wire.
45. 18. In a toy railway accessory, a supporting means formed entirely of wire, an adjustable signalling means attached thereto, and means for locking it in position.
50. 19. In a toy railway accessory, a supporting means formed entirely of wire, and a plurality of adjustable signalling means attached thereto and superimposed one above another.
55. 20. A toy railway accessory including a supporting means formed entirely of wire and having projections forming ladder steps, and a warning or signal means attached to said wire supporting means.

Signed at Buffalo, New York, this 2nd day of November, 1922.

ALAN R. FERGUSSON.
